US00D390706S

United States Patent [19]

Hohlbein et al.

[11] Patent Number: Des. 390,706

[45] Date of Patent: **Feb. 17, 1998

[54] TOOTHBRUSH

[75] Inventors: **Douglas J. Hohlbein**, West Trenton; **Kenneth Gerald Waguespack**, North Brunswick, both of N.J.[73] Assignee: **Colgate-Palmolive Company**, New York, N.Y.

[**] Term: 14 Years

[21] Appl. No.: 61,489

[22] Filed: Oct. 24, 1996

[51] LOC (6) Cl. 04-02

[52] U.S. Cl. D4/104

[57] CLAIM

The ornamental design for a toothbrush, as shown and described.

DESCRIPTION

FIG. 1 is a top plan view of a toothbrush showing our new design;

FIG. 2 is a left side elevational view thereof;

FIG. 3 is a bottom plan view thereof;

FIG. 4 is a right side elevation view thereof;

FIG. 5 is an elevational view as seen from the head end thereof;

FIG. 6 is an elevational view as seen from the handle end thereof;

FIG. 7 is a perspective view thereof from the top of the brush; and,

FIG. 8 is a perspective view thereof from the bottom of the brush;

FIG. 9 is a top plan view of a second embodiment of the design shown in FIGS. 1-8;

FIG. 10 is a left side elevational view thereof;

FIG. 11 is a bottom plan view thereof;

FIG. 12 is a right side elevation view thereof;

FIG. 13 is an elevational view as seen from the head end thereof;

FIG. 14 is an elevational view as seen from the handle end thereof;

FIG. 15 is a perspective view thereof from the top of the brush; and,

FIG. 16 is a perspective view thereof from the bottom of the brush.

The broken line showing of bristles in FIGS. 9-16 is for illustrative purposes only and forms no part of the second embodiment.
